UNITED STATES PATENT OFFICE.

JAMES ROBERTSON PORTER, OF EXMOUTH, ENGLAND.

PROPELLION MEANS FOR VESSELS.

Application filed March 2, 1922. Serial No. 540,599.

To all whom it may concern:

Be it known that JAMES ROBERTSON PORTER, engineer, a subject of the King of Great Britain, residing at "Tornado," The Point, Exmouth, in the county of Devon, England, has invented a certain new and useful Improvement in or Relating to Propulsion Means for Vessels, of which the following is a specification.

10 This invention has for its object to provide improvements in aeronautical machines and means for the propulsion of same, parts of which improvements are also applicable to marine vessels.

15 According to this invention I employ as a means of propulsion a casing or fluid channel having the form of a Venturi tube and a propeller so located as to draw air through said casing or fluid channel, the aperture of 20 the upper part or entrance end of said fluid channel being reduced or curtailed, for instance by radial guides which may be utilized as passages, for the purposes hereinafter referred to.

25 As an example, a propeller may be situated at the lower enlarged end of the Venturi tube shaped casing or passage, or as in another example, the propeller may be located at or about the narrowest portion of 30 the Venturi shaped passage, and the latter may be provided with radial guides disposed in front of the propeller, and made of such width at their central cross section that the fluid channel is considerably reduced thereby, the said radial guides may increase in width towards their outer ends, their sides in plan conforming to lines radiating from the axis of the fluid channel. The said radial guides may also be employed 35 with the construction where the propeller is situated at the lower enlarged or exit end of the Venturi tube.

In applying the invention to an aeronautical machine of the helicopter type, I may 40 utilize the interior of the radial guides as passages for giving access to the pilot's seat which is located in an elongated chamber disposed axially in an air channel which takes the form of a Venturi tube.

45 In one modification the said air channel is centrally located in an outer and more or less spherical enclosure or skin, supported by a series of semicircular ribs or frames abutting on top and bottom ring-frames 50 which enclose the inlet and outlet of the air

channel, and are supported on suitable vertical columns or standards.

In a further modification the outer and more or less spherical enclosure or skin may be so constructed that its upper part will 60 open out and form a parachute when required.

I will first describe my invention as applied to an aeronautical machine of the helicopter type, for which purpose I will refer to,

Figs. 1 to 6 of the accompanying drawings, in which—

Fig. 1 is a vertical section,

Fig. 2 is a plan,

Fig. 3 is a section on line X X of Fig. 1.

Fig. 4 is a diagrammatic sectional elevation of the aeronautical machine showing a modified arrangement of the propeller.

Fig. 5 is a similar view to Fig. 4 showing 75 how the outer enclosure of the aeronautical machine may be utilized as a parachute.

Fig. 6 is a plan of Fig. 5.

I will later describe the invention as applied to the propulsion of marine vessels, 80 for which purpose I will refer to Figures 7 and 8, of which—

Fig. 7 is a longitudinal section, and

Fig. 8 an end view of Fig. 7 from the left.

Referring now to Figs. 1 to 3, the invention is here shown as applied to aeronautical machines of the helicopter type such as described in my British Patent No. 134416 and more particularly Fig. 5 of the specification of the said patent. *a* is an engine 90 mounted on the central shaft *b* so as to drive the propeller *c* direct or by suitable gearing. The exhaust from the engine *a* may be discharged directly on to the surface of a revolving fuel tank *d* as indicated by the pipes *e*, *e* for the purpose of heating the fuel in the said tank, the fuel or fuel vapour from the said tank *d* being conveyed to the engine *a* in any suitable manner.

The propeller blades *c* are fixed on the 100 radial arms of the rotary tank *d*. The rotary fuel tank shown may be omitted and other fuel tanks provided in which case the propeller blades will be mounted on a suitable frame or radial arms.

Advantage may be taken of the flow of air in the Venturi channel *f*, the static pressure of which is low, to induce a current of air through the space *g* surrounding the engine cylinders.

In applying the present invention to the helicopter advantage is taken of the construction of the Venturi tube f to provide accommodation for the pilot in the top portion of the central body h immediately above the rotary tank d and engine a , means of access thereto being obtained by a series of radial passages i , leading from the annular enclosure surrounding the Venturi shaped channel f , and constituting the radial guides already referred to. j and k are hand-wheels by which the pilot controls the fuel and air supply to the engine.

The said radial passages or guides i have the shape of a flattened oval or spool in section as shown more clearly in Fig. 3, and may have a height equal to the shrouding l above the propeller c and embrace radial members m which connect the upper ends of the standards n with a central standard o disposed in alignment with the central engine shaft b . The pilot's seat p is located directly above the engine a and tank d , and within the central body or fuselage h which is circular in section and cylindrical in shape. The height of the vertical shrouding l above the propeller is preferably the same as that below, the air channel through the machine having a varying cross section forming the Venturi tube f . Observation outwardly is secured from the pilot's seat through the radial windows q for which purpose the outer skin l which may be spherical in form is glazed opposite these points.

35. The radial passages which form the guides i not only provide means of access for the pilot, but by their external shape and location in the Venturi tube f have the effect of causing a lifting effect upon the machine for the following reason.

The current of air through the machine induced by the propeller, if there were no radial passages, would produce a reduction of static pressure on the skin of the annular body, which pressures would neutralize each other, the reduction of static pressure on the surface above the propeller being counteracted by a similar reduction of pressure on the surfaces below.

50. In the present invention radial passages are used above the propeller, the cross sectional area of the Venturi-tube being reduced in consequence of the space occupied by the passages, and this is particularly the case at the section where the radial passages have a maximum width, in which the cross section of the Venturi tube is reduced to half its original area.

By the Venturi law it is known that the static pressure of the fluid on the walls of the channel is reduced in proportion to the square of the air velocity. Comparing the pressure at a reduced area of 50 per cent caused by the radial passages above the propeller with the corresponding section of the

channel below the propeller, where there are no radial passages, the velocity of the air at this lower section is half that occurring at the corresponding section above the propeller. As the reduction of static pressure on the skin varies as the square of the velocity, it follows that the reduction of static pressure at the reduced area above the propeller is four times that of the corresponding section below. If A is the area in square feet of a circumferential strip of Venturi surface one foot in depth at the reduced area then $2A$ equals the area of a similar strip at the corresponding section below, and if V is the velocity in feet per second of the air at the reduced area the velocity at the corresponding lower point is $\frac{V}{2}$. If w is the weight of a cubic foot of air and g the gravity constant, we have a reduction of static pressure on the circumferential strip one foot deep at the reduced area of $\frac{wAV^2}{2g}$ compared with a reduction of pressure on the corresponding strip below the propeller of $\frac{wAV^2}{4g}$ which signifies that there is an unbalanced force on the machine, the vertical component of which tends to raise the machine.

With respect to the pressure on the skin of the guides or radial passages only, the upward and downward pressures neutralize.

For alighting on land, a series of spring controlled wheels r may be provided, the vertical rods s holding said wheels being free to slide within downward extensions of the standards p .

t is the platform by which the pilot or a passenger may direct the course of the machine as described in my said prior British patent.

Referring now to Fig. 4. In the modified construction here shown the propeller c is situated at, or just beyond, the lower enlarged end of the Venturi shaped passage or casing f , and is adapted to draw air through said passage, the aperture of the upper part of which is reduced or curtailed by the radial guides or passages i .

The propeller c may be driven by an engine located as indicated at a or in other suitable manner.

Except that the propeller c operates at the lower end of the Venturi shaped channel f to draw air therethrough the operation will be as in the hereinbefore described construction.

Referring now to Figs. 5 and 6 which show one method whereby the outer enclosure or skin of the helicopter is adapted to form a parachute when required.

The upper part of the outer enclosure or skin l is here shown as divided into a number of movable segments 2 which are hinged

at their upper ends as at 3 to the ring frame which supports the upper end of the Venturi shaped channel *f*, their lower ends being secured by cords or wires 4 suitably guided and fastened together in a position convenient of access to the pilot so that the said cords or wires and the corresponding segments 2 may be released to the required extent to form the parachute 10 when required.

The full lines in Figs. 5 and 6 show the parachute segments 2 in the closed position forming the outer skin of the more or less spherical outer enclosure or skin of the 15 helicopter, whilst the dotted lines show the segments 2 extended to form the parachute.

As applied to the propulsion of marine vessels I may employ an arrangement such as shown in Figs. 7 and 8 to which I will 20 now refer; similar letters will be employed for similar parts, where applicable.

The propulsion device here shown consists of a water channel in the form of a Venturi tube *f* and consisting of a casing 25 in the narrowest part of which is located the propeller *c* carried upon a shaft *a* running on bearings mounted on an axially located body part *v* which carries the radial guides *i* extending across the Venturi channel *f*; the rear part *v'* of the central body 30 *v* may rotate with the propeller. The said radial guides *i* reduce or curtail the aperture of the said Venturi-shaped channel *f* where it leads up to the propeller *c* and the 35 operative effect will be the same as that already described with reference to the helicopter.

The outer skin *l* of the Venturi channel *f* will be of more or less spherical shape as 40 shown in the drawings, and attached to the ship by one or more projections *w*.

What I claim as my invention and desire to secure by Letters Patent is:—

1. As a means of propulsion a fluid channel having the form of a Venturi tube, a propeller so located as to draw air through said channel, and means consisting of radial guides whereby the upper part or entrance end of the Venturi-shaped channel in front 50 of the propeller is reduced or curtailed.

2. As a means of propulsion a fluid channel having the form of a Venturi tube, a propeller so located as to draw air through said channel and radial guides of spool 55 shaped cross section extending across the upper part or entrance end of the said fluid channel, said guides being of such width at their central cross section that the fluid channel is considerably reduced thereby.

60 3. An aeronautical machine of the helicopter type provided with a fluid channel having the form of a Venturi tube, a propeller so located as to draw air through said fluid channel, an axially elongated chamber containing the pilot's seat and disposed cen-

trally of and surrounded by said Venturi shaped fluid channel, and radial guides extending across the upper part of the said Venturi shaped channel to said axially elongated chamber.

4. An aeronautical machine of the helicopter type provided with a fluid channel having the form of a Venturi tube, a propeller so located as to draw air through said fluid channel, an axially elongated chamber 70 containing the pilot's seat and disposed centrally of and surrounded by said Venturi shaped fluid channel, and radial guides extending across the upper part of the said Venturi shaped channel to the central 75 elongated chamber, said radial guides being formed as passages whereby they may be utilized for giving access to the central elongated chamber.

5. An aeronautical machine of the helicopter type provided with a fluid channel having the form of a Venturi tube, a propeller so located as to draw air through said fluid channel, an axially elongated chamber containing the pilot's seat and disposed centrally of and surrounded by said Venturi shaped fluid channel, radial guides of hollow spool shaped cross section extending across the upper part of the said fluid channel to 80 said axially elongated chamber whereby said 85 guides may be utilized as passages for giving access to the said chamber, and means for supporting said radial guides consisting of radial members extending from a column within the central chamber to vertical 90 columns which connect top and bottom rings enclosing the inlet and outlet of the Venturi shaped fluid channel.

6. An aeronautical machine of the helicopter type provided with a fluid channel 105 having the form of a Venturi tube, a propeller so located as to draw air through said fluid channel, an axially elongated chamber containing the pilot's seat and disposed centrally of and surrounded by said Venturi 110 shaped fluid channel, an outer spherical skin supported by a series of semi-circular ribs, abutting on top and bottom ring frames, which enclose the inlet and outlet of the Venturi shaped fluid channel, and radial 115 guides extending across the upper part of the said Venturi shaped channel to said axially elongated chamber.

7. An aeronautical machine of the helicopter type provided with a fluid channel 120 having the form of a Venturi tube, a propeller so located as to draw air through said fluid channel, an axially elongated chamber containing the pilot's seat and disposed centrally of and surrounded by said Venturi 125 shaped fluid channel, an outer spherical skin supported by a series of semi-circular ribs, abutting on top and bottom ring frames, which enclose the inlet and outlet of the Venturi shaped fluid channel, and radial 130

guides extending across the upper part of the said Venturi shaped channel to said axially elongated chamber, means whereby the upper part of the spherical skin is made to spread out to form a parachute when required.

8. An aeronautical machine of the helicopter type provided with a fluid channel having the form of a Venturi tube, a propeller so located as to draw air through said fluid channel, an axially elongated chamber containing the pilot's seat and disposed centrally of and surrounded by said Venturi shaped fluid channel, an outer spherical skin

supported by a series of semi-circular ribs, 15 abutting on top and bottom ring frames, which enclose the inlet and outlet of the Venturi shaped fluid channel, and radial guides extending across the upper part of the said Venturi shaped channel to said axially elongated chamber, means whereby the upper part of the spherical skin is constructed of segments hinged at their upper ends and releasably secured at their lower ends, and whereby the said segments when released to the required extent open outwards on their hinges to form a parachute.

JAMES ROBERTSON PORTER.
